CLAIM

The ornamental design of a dryer, as shown and described.

DESCRIPTION

FIG. 1 is a perspective view of the dryer showing my new design;

FIG. 2 is a perspective view thereof;

FIG. 3 is an exploded view thereof;

FIG. 4 is a front view thereof;

FIG. 5 is a back view thereof;

FIG. 6 is a right side view thereof;

FIG. 7 is a left side view thereof;

FIG. 8 is a top view thereof; and,

FIG. 9 is a bottom view thereof.

The broken lines shown in FIG. 2 are for illustrative purposes only and form no part of the claimed design.
